ARROW AND PROJECTOR THEREFOR
Erhardt N. Peters, 402 E. Court St., Ludington, Mich.
Filed Jan. 6, 1960, Ser. No. 757
7 Claims. (Cl. 124—23)

This invention relates to improvements in archery arrows and to bow-type projectors therefor.

The primary object of the invention is to provide a bow-type projector for shooting archery arrows in response to reaction of one end only of a bow-type projector held by an outstretched arm of a person to extend longitudinally of the arm with its other end attached to the arm, and a bowstring terminally attached to the reactive end of the bow and to the arrow to sling the arrow in shooting, and whereby a novel and unique device is produced that is interesting as a toy and useful either for target practice or as a weapon in hunting.

Another object is to provide an arrow projector according to the foregoing, and means for terminally attaching the bowstring to an arrow so that in shooting or projecting, the arrow backlash will be prevented.

Still another object is to provide means for attaching the bowstring to an intermediate portion of a conventional archery arrow to facilitate projecting, or shooting, the arrow and to obviate the manufacture of special arrows for shooting by the projector.

These, together with other objects and advantages which will become subsequently apparent, reside in the details of construction and operation as more fully hereinafter described and claimed, reference being had to the accompanying drawings forming a part hereof, wherein like numerals refer to like parts throughout, and in which:

FIGURE 1 is a fragmentary view in side elevation of a preferred embodiment of the invention, partly in broken lines, with the bow-type projector attached to an arm of a person in position for ejecting or shooting an arrow;

FIGURE 2 is an enlarged fragmentary view in side elevation, partly in section;

FIGURE 3 is a view in vertical cross-section taken on the line 3—3 of FIGURE 2;

FIGURE 4 is an enlarged fragmentary view in side elevation of a modified embodiment of the projector;

FIGURE 5 is an enlarged fragmentary view in side elevation of another modified embodiment of the projector; and

FIGURE 6 is an enlarged fragmentary view in side elevation of still another modified embodiment of the projector.

Referring to the drawing by numerals, and first to FIGURES 1 to 3, according to the preferred embodiment of this invention, the arrow projector, designated generally by the numeral 1, comprises an elongated bow member 3 tapering forwardly from a butt end 5 to a resilient reactive front end portion 7.

The bow member 3 is formed of a stick, or rod, of resilient wood, preferably, and pre-shaped with the front end portion 7 thereof curved laterally rearwardly. An intermediate hand grip portion 9 is formed on the bow member 3 and a suitable arm band 11 is fixed, in any desired manner, on the butt end 5 so that the bow member 3 may be grasped intermediate its ends in one hand 13 of an arm 15 of a person, with the arm band 11 encircling the forearm 17 adjacent the elbow 19, and whereby the bow member 3 may be held in the outstretched arm 15 longitudinally thereof with the front end portion 7 curved laterally of the forearm 17 and extending forwardly of the hand 13.

The bowstring 21, suitably attached terminally to the tip 23 of the front end portion 7 to be pulled rearwardly,

2

is substantially shorter than the bow member 3, and provided with means on its free end for releasably coupling to means, presently described, on an arrow 25. The coupling means on the bowstring 21 preferably comprises 5 a terminal loop 27 and the means on the arrow 25 comprises a nock member 29.

The nock member 29 comprises a split, resilient band 31 which may be formed of any suitable material such as metal, plastic, or the like, and which is adapted to be 10 attached to and tightly grip the conventional archery arrow shaft 33 at any desired position between the ends of said shaft 33.

The band 31 of the nock member 29, at the split thereof, is formed with a pair of outstanding, opposite, spaced 15 apart outwardly tapering lugs 35 of concavo-convex form and which each form a rearwardly opening recess 36 for receiving the loop 27. Each lug 35 includes a rearwardly and outwardly curving convex forward surface 38 and a rearwardly and outwardly curving concave rear surface 39 defining the recess 36. If desired, the loop 27 may be utilized as a knot which may also be otherwise formed on the string 21 and the string releasably inserted between the lugs 35 with the loop 27 used as a knot behind the lugs 35. The band 31 is preferably formed 20 with inturned side edges, as at 37, to bite into and facilitate gripping the archery arrow shaft 33. And it will be appreciated that concavo-convex form of the lugs will enable the latter to readily be extracted from engagement with the rear portion of the loop 27 upon movement of 25 the member 29 past the end portion 7 thereby removing any tendency of the loop 27 to catch on the lugs 35 and cause deflection of the arrow or backlash of the latter.

In the modified embodiment shown in FIGURE 4, the bow member 39 is formed, forwardly of and closely adjacent to the hand grip portion 41, with transverse coils 43 for increasing the resiliency of the bow member.

In the modified embodiment shown in FIGURE 5, the bow member 45 is formed with a single coil 47 forwardly of and close to the hand grip portion 49 and with the axis 40 of the coil 47 transverse to the bow member for increasing the resiliency of said member.

In the modified embodiment shown in FIGURE 6, the bow member 51 is formed adjacent to and forwardly of the hand grip portion 55, close thereto, with a series of 45 lateral loops 53 for the same purpose as the loops 43, 47.

In the modified embodiments, the bow member may be formed either tapered or not, and of resilient rod material.

The use and operation of the invention will be readily understood. The bow member 1 is attached to the forearm 17 of an arm 15 and grasped by the hand 13 at the hand grip portion 9, preferably with the front end portion 7 downturned as shown in FIGURE 1. With the lugs 35 inserted in the loop 27 and preferably over the top of the arrow 3, and the other hand 57 of the person grasping the tail end of the arrow shaft 33, the arm 15 is held straight out and the arrow shaft 33 pulled rearwardly to flex the front end portion 7 rearwardly to the desired extent. Then the person may release the tail end of the arrow shaft 33 at will, whereupon the front portion 60 7 of the bow member 3 will react forwardly to project the arrow 25 which will be released from the bowstring 21 by the loop 27 sliding off the lugs 35, or from between said lugs if the loop 27 is used as a knot, in the manner previously described.

As will be seen, the projector 1 will function to sling arrow 25 forwardly with considerable force. Also, as will be clear, the bow member may be grasped and attached to the arm for turning of the front end portion 7 upwardly or sidewise so that the arrow may be positioned 65 for shooting above the arm 15 or at either side thereof as desired instead of under the arm as shown in FIGURE 1.

It is to be understood that the nock member 29 may be adjustably positioned longitudinally on the arrow 25 to provide the desired balance of the latter and for obtaining different flight characteristics. The split band 31 may have its confronting ends spread apart to enable the position of the nock member 29 to be changed after which the inturned side edges 37 thereof will resiliently grip the arrow 25 to maintain the nock member 29 in its new position.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A projector for an arrow comprising an elongated member having a butt end and a front end portion, said front end portion being forwardly tapered to increase the resiliency thereof, a hand grip portion on said member intermediate the ends of the member for grasping of the member by a hand to hold said member longitudinally of an outstretched arm with said front end portion forwardly of the hand, means, on said butt end portion adapted to completely encircle and thereby attach said butt end to said arm, a nock member attachable to an intermediate portion of an arrow shaft, and a bowstring terminally attached to the tip of said front end portion and to said nock member and slidably releasable from said nock member in response to projection of said arrow shaft whereby, in response to manual pull on a rear portion of the arrow shaft, said string will be pulled rearwardly to flex said front end portion rearwardly to react forwardly and project the arrow shaft in response to manual release of the rear portion of said shaft.

2. The combination of claim 1, said means on said butt end comprising an arm band.

3. A projector for an arrow comprising an elongated resilient member having a butt end and a front end portion, said front end portion being forwardly tapered to increase the resiliency thereof, a hand grip portion on said member intermediate the ends of the member for grasping of the member by a hand to hold said member longitudinally of an outstretched arm and with said front end portion forwardly of the hand, means on said butt end portion adapted to completely encircle and thereby attach said butt end to said arm, a nock member attachable to an intermediate portion of an arrow shaft, and a bowstring terminally attached to the tip of said front end portion and to said nock member and slidably releasable from said nock member in response to projection of said arrow shaft whereby, in response to manual pull on a rear portion of the arrow shaft, said string will be pulled rearwardly to flex said front end portion rearwardly to react forwardly and project the arrow shaft in response to manual release of the rear portion of said shaft, said nock member comprising a split resilient band for attachment to an arrow shaft in friction locking engagement therewith and for adjustment longitudinally of said shaft.

4. The combination of claim 1, said nock member having a rearwardly opening hook thereon, said string having

a terminal coupling end slidably engageable with said hook.

5. The combination of claim 1, said elongated member having lateral loops formed therein between said hand grip portion and said front end portion.

6. A projector for an arrow comprising an elongated resilient member having a butt end and a curved front end portion, said front end portion being forwardly tapered to increase the resiliency thereof, a hand grip portion on said member intermediate the ends of said member for grasping of the member by a hand to hold said member longitudinally of an outstretched arm with the front end portion forwardly of the hand, means on said butt end portion adapted to completely encircle and thereby attach said butt end to said arm, and a bowstring terminally attached at one end to the tip of said front end portion and including means on the other end adapted to be releasably engaged with a laterally projecting hook-like nock secured to the mid-portion of an arrow shaft whereby in response to manual pull on the rear portion of the arrow shaft, said string will be pulled rearwardly to flex said front end portion of said resilient member rearwardly to react forwardly and project the arrow shaft in response to manual release of the rear portion of said shaft.

7. A projector for an arrow comprising an elongated resilient member having a butt end and a front end portion, said front end portion being forwardly tapered to increase the resiliency thereof, a hand grip portion on said member intermediate the ends of the member for grasping of the member by a hand to hold said member longitudinally of an outstretched arm with said front end portion forwardly of the hand, means on said butt end portion for attaching the same to the arm, a nock member attachable to an intermediate portion of an arrow shaft, and a bowstring terminally attached to the tip of said front end portion and to said nock member and slidably releasable from said nock member in response to projection of said arrow shaft whereby, in response to manual pull on a rear portion of the arrow shaft, said string will be pulled rearwardly to flex said front end portion rearwardly to react forwardly and project the arrow shaft in response to manual release of the rear portion of said shaft, said nock member comprising a split resilient band for attachment to an arrow shaft in frictional locking engagement therewith and for adjustment longitudinally of said shaft, said split resilient band having a transversely convexed inner surface forming in-turned opposite side edges adapted to bite into and to facilitate the frictional gripping of the mid-portion of an arrow shaft by the split band.
